UNITED STATES PATENT OFFICE

ARTHUR A. ADAMS, OF BROOKLINE, MASSACHUSETTS, ASSIGNOR TO RAILWAY SAFETY SWITCH LOCK COMPANY, OF SEATTLE, WASHINGTON, A CORPORATION OF WASHINGTON

LOCKING MECHANISM FOR SWITCH STANDS

Application filed March 16, 1929. Serial No. 347,666.

This invention relates to locking mechanisms for switch stands, and, with regard to certain more specific features thereof, to key-operative detent mechanism suitably housed and protected.

The invention has particular application to switch operating devices known as "vertical switch stands", these stands being of a type in general use on railroads at the present time.

The invention has for one of its objects to provide an inexpensive, compact and highly efficient locking mechanism for the switch operating lever of a switch stand.

Another object of the invention is to provide a detachable housing unit containing the detent and key-operative mechanism for controlling the detent, which unit may be quickly and conveniently attached to the stand without substantial modification of the standard equipment. While the invention in one of its aspects involves this detachable unit characteristic, it, nevertheless, in other aspects has features which might serve as well in a housing integral with the switch stand.

Still another object is to so arrange and associate the detent with the stand that it operates directly in conjunction with a vertically movable clutch part, whereby opening of the clutch is directly prevented by the detent.

Another object of the invention resides in the provision of extremely simple operating mechanism for controlling the movements of the detent, this mechanism being inexpensive to produce, easy to assemble, extremely sturdy and particularly effective in preventing movement of the detent except in an authorized manner.

The invention, accordingly, consists in various features of construction, combinations of elements and arrangements of parts which will be exemplified by the construction hereinafter set forth and illustrated in the accompanying drawings. The scope of the application of the invention will be indicated in the appended claims.

In the drawings, Figure 1 is a perspective

view of a switch stand embodying the invention.

Figure 2 is an enlarged view of the lever controlling mechanism shown in Figure 1.

Figure 3 is a view of the detent housing shown in Figure 2 with the detent actuating mechanism shown in another position.

Figure 4 is a sectional view of the detent mechanism taken substantially along the line 4-4 of Figure 2.

Figures 5, 6, 7 and 8 are views of the key-operative mechanism.

Referring now more particularly to the drawings, there is indicated in Figure 1 a switch stand having a pedestal 10, the upper end of which is provided with a squared recess 11. The pedestal is provided with a suitable journal, not shown, and a cylindrical portion 12 of a spindle 13. The spindle is squared throughout the major portion of its length and is exteriorly fitted with a squared member 14 and secured thereto by a bolt 15 passing through a bolt hole in the squared member 14, a part of the bolt serving as a key in a semi-cylindrical groove 16 formed in the spindle 13, as shown in Figure 2. The member 14 has at the top an extended and curved arm 17, the end of which provides a means for pivotally supporting a forked switch-operating lever 18, the forked ends 19 of which provide a yoke embracing a vertical movable clutch body 21 between upper and lower lugs 22 and 23 formed on opposite sides of the clutch body at the upper end thereof. The clutch body has sliding sleeve action on the squared member 14 under the control of the lever 18. By this action, a clutch element 24 at the bottom end of the clutch body is adapted to be moved into and out of position within the squared recess 11 of the pedestal.

The mechanism as so far described, is at present standard equipment, including the bolt 15. Referring now to Figure 2, 3 and 4 of the drawings, a cast housing 30 is formed with a laterally extending plate 31 having an upper flange 32 and a bolt hole 33. The flange 32 extends along the plate 31 and then at right angles as indicated at 34. On the front side of the housing, there is another short laterally extending flange 35 (see Fig.

ure 1). These flanges are formed to fit around the sides and top of the squared member 14 of the switch stand. The original bolt 15 may be removed and a slightly longer bolt substituted to accommodate the thickness of the flange 31. In this way the housing is securely fixed to the switch stand by the substitute bolt 15.

The cast housing has a hollow body 36 rounded at the top, as indicated at 37, and formed with depending hollow arm 38, partially closed by an angle plate 39 separately produced and fitted to the housing. A cast web 40 divides the attached portion of the housing from the portion which contains the actuating locking mechanism.

The housing 30 is provided with a boss 41 which is bored to receive a barrel 42 containing a key-operative mechanism, indicated generally at 43, in Figures 5, 6 and 8. The forward face of the barrel 42 has pivoted thereon a spring pressed guard 44 normally held in position over a key hole 45 in the barrel. The guard is provided on one face with one or more irregularities 46 adapted to conform to the side of a key 47, whereby the key may be located against the guard and used to move the same against the spring pressure until the key hole is exposed, whereupon the key may be fitted to the actuating mechanism in the barrel.

The key-operative mechanism comprises a crank 50, having a crank pin 51, to which is loosely connected, as at 52, a depending link 53. The lower end of the link 53 is formed with extending bosses 54 on either side of the link, and these bosses are adapted to ride up and down in the housing between a wall 55 thereof and a detent member 56, which is pivoted in the housing at 57. This detent member has a locking nose 58, a shank 59, and a laterally extending bifurcated arm 60 formed on its lower side, as at 61, to receive the lugs 54 of link 53.

The operation of the device is as follows. Assuming the switch stand to be in a normal locked position with the clutch body 21 down and the squared clutch member 24 in the squared recess 11 of the pedestal 12, the switch lever 18 will be in a lowered position with respect to that shown in Figure 1 of the drawings. The operator inserts his key into the barrel 42, turns the key substantially 180 degrees, moving the crank 50 of the key-operative mechanism from the position shown in Figure 2 of the drawings to that shown in Figure 3. This lifts the link 53, which picks up the laterally extending arm 60 of detent 59, swinging it around the pivot 57, with drawing the detent nose 58 entirely within the hollow arm 38 of the housing. This removes the opposition to the upward movement of the clutch body 21. The operator now raises the switch lever 18, which pivots around a bolt 20, and this, by reason of its

engagement with lugs 22, raises the clutch body 21 separating the squared clutch part 24 from its engagement with the pedestal 10. The lever 18 is then moved rotatively, carrying with it the spindle 12, which latter is connected to the switch rail to be operated. This movement may be through an arc of ninety degrees or one hundred and eighty degrees as desired, after which the lever arm may be dropped, allowing the clutch body 21 to reset itself within the pedestal. During this movement, the key 47 is retained within the lock, but may now be removed by reversing the direction of movement of the key, which affects a corresponding reverse movement of the crank lever 50 and a downward movement of the link 53. During this downward movement, the bosses 54 of link 53 have a wedging action between the wall 55 of the housing and the shank 59 of the detent. This urges the detent in the opposite direction around pivot 57, protruding the nose 58 of the detent again into the path of the clutch body 21, and at this point the operator's key may be withdrawn and the detent is reset in locking position. The locking movement of the detent is limited by engagement of one side of the shank 59 with the angle plate 39. In the locking position, the bosses 54 are positioned between the shank 59 of the detent and the wall 55 of the housing. This prevents movement of the detent to unlocking position even under conditions of extreme leverage applied to the detent nose. It is to be noted, however, that the detent nose is positioned at this time against one face of the squared member 14, so that it is practically impossible to apply substantial leverage to the detent nose. While it is not claimed that any part of the present invention resides in the specific key-operated device contained within the barrel 42, this mechanism has been shown somewhat in detail for the purpose of illustrating the point that the operation of the detent in both directions is dependent upon movement of the key in both directions, and also that the key is held against withdrawal except when the detent nose is in locking position. A key tang 70 is inserted through the key hole 45, which simultaneously fits the hollow stem 71 of the key over a reduced end 72 of an arbor 73. A dog 74 is pivoted at 75 on a partition 76 fixed in the barrel at the rear thereof. This dog is spring pressed into the position shown in Figure 6 by a spring 77. Rotation of the key on the arbor 73 brings the tang of the key against the edge 78 of a flange 79 on the arbor. Continued rotation of the key carries with it the flange, the arbor and the crank 50 fixed to the arbor, after first releasing the locking lug 80 on the dog 74 from its engagement with the arbor. It will be obvious that the key may not be withdrawn until rotated in the reverse direction, during

which action the opposite side of the tang 70 picks up an edge 81 on the flange 79 of the arbor, and moves the arbor in the opposite direction relocating the detent through the mechanism previously described. The key may then be withdrawn from the barrel.

Attention is directed to the fact that the locking mechanism is extremely compact and sturdy, and that the action of the detent nose is directly upon the vertical movable clutch. The detent when locked, although with an exposed part, is nevertheless protected and reenforced in such a way that unauthorized manipulation is substantially impossible.

15 What I claim is:—

1. A switch stand for railroads, having in combination, a housing having a key-operative mechanism and a detent controlled by said mechanism, a lever and connections for throwing a switch, clutch means controlled by movement of the lever, the detent being arranged for movement toward and away from the clutch means respectively to lock and unlock the clutch.

25 2. A switch stand, having in combination, an operating lever, a clutch part movable by said lever, a housing having a key-operative mechanism therein, and a detent member movable into and out of locking position under control of the key-operative mechanism, said housing being at a location on the stand that presents the detent opposite the clutch part and prevents movement thereof by the lever until the detent is key-operated 35 to unlocking position.

3. In a switch stand, in combination, a spindle, a sleeve arranged for rotary movement therewith but movable longitudinally relatively to the spindle, a lever for effecting both said movements, connections from the lever to a switch rail, and a housing on the stand containing a movable detent and a key-operative mechanism for moving the detent, one movement of the detent being to a position in the path of the longitudinal movement of the sleeve.

4. A housing unit for application to a switch stand, said unit having a key-operative mechanism, a movable detent connected 50 to said mechanism and a nose on said detent protruding from said housing for locking, and retractile into the housing for unlocking.

5. A housing unit for application to a 55 switch stand, said unit having a pivoted detent and a key-operative mechanism for moving the same to locking and unlocking positions, the pivoted detent having a cam face and an arm laterally extending from the face, 60 a link in said key-operative mechanism having a member movable between an inner face of the housing and the cam face of the detent to move the detent to locking position, said member being adapted upon reverse action of 65 the key-operative mechanism to pick up the

laterally extending arm and move the detent to unlocking position.

6. In a locking device for switch stands, a housing having a key-operative mechanism therein, a detent pivotally mounted in said housing having a nose movable from a retracted position within the housing to a locking position projected out of the housing, and a link in the key-operative mechanism having a wedging action between the housing and the detent to move the latter to locking position.

7. In a locking device for switch stands, a housing having a key-operative mechanism therein, a detent pivotally mounted in said housing, having a depending arm with laterally offset locking nose and having also a laterally extending arm, a member in the key-operative mechanism providing a wedge movable between a wall of the housing and said depending arm to throw the locking nose to locking position, said member being adapted in an opposite direction of movement to pick up the laterally extending arm and withdraw the locking nose.
